UNITED STATES PATENT OFFICE.

SAMUEL GREEN, OF LAMBERTVILLE, NEW JERSEY, ASSIGNOR TO S. GREEN AND C. ARNETT.

WINDOW-SHUTTER BOLT.

Specification of Letters Patent No. 10,220, dated November 8, 1853.

To all whom it may concern:

Be it known that I, SAMUEL GREEN, of the town of Lambertville, in the county of Hunterdon and State of New Jersey, have 5 invented a new and useful Improvement in Bolts or Locks for Fastening Window Shutters, Doors, &c., which I call the "Double Self-Locking Bolt;" and I do hereby declare that the following is a full, clear, and exact 10 description of the construction and operation of the same, reference being had to the annexed drawings, making a part of this specification, in which—

Figure 1 is a perspective view of the bolt. 15 Figs. 2, 3 and 4 are sectional views, with the top or front of the case removed thereby presenting the several parts to view; Fig. 2 representing the instrument fully or doubly locked; Fig. 3 representing it with one stop 20 (the spring) unlocked, and the bolt pressed back until arrested by the other stop to wit, the drop bolt, and Fig. 4 representing it entirely unlocked, and the main bolt withdrawn, or pressed quite back.

25 Of the several figures, A A is the case or frame inclosing the main bolt, together with the spring and drop bolt or tumbler, and through which the said parts pass and repass when being locked or unlocked.

30 B B is the main bolt.

C C is a slit or aperture in the top or front of the case (seen only in Fig. 1) through which a rim or knob D is inserted in the main bolt, for the purpose of moving 35 and removing it by the pressure of the hand.

E is the portion of the case or frame (separate from the part A A) to receive the end of the bolt when locked.

F is a spring with one end inserted in the 40 main bolt, and the other end falling below it, so as to act as a stop, by striking against a shoulder in the case at G.

H is a drop bolt or tumbler fitted loosely 45 into a vertical groove in the back part of the main bolt and lock of the spring, and there-

fore not in sight, even when the top or front of the case is removed, except the small part of it falling below the spring into its place or notch in the case. Its situation and shape are indicated by the dotted lines upon the 50 main bolt.

I is a key hole, so arranged that the key may act first upon the spring, and then upon the drop bolt as hereinafter described.

The bolt is operated as follows: Being 55 unlocked or withdrawn, it is locked simply by pressing the hand against the pin or knob D until the bolt is fully extended, at which point, both the spring and drop bolt or tumblers fall into their places in the 60 notch in the case, and act as stops. To unlock the bolt the key is inserted with one hand within the top plate or front of the case, but held back against it, while it is turned so far as to lift the end of the spring 65 sufficiently out of its place, while with the other hand, the operator presses the bolt back so far that the end of the spring shall rest upon the part of the case just beyond the notch, and until the drop bolt striking 70 against the shoulder at the end of the notch, presents the further movement of the main bolt. The key is then pressed in to the bottom of its cell, to act against the drop bolt instead of the spring, and being further 75 turned, raises the drop bolt out of the notch in the case, at which time, with the hand still upon the knob, the operator presses the main bolt back to its place in the case.

What I claim as my invention and wish 80 to secure by Letters Patent, is—

The spring and drop bolt or tumbler arranged with reference to each other, and the notch in the case as described, and so formed and located that they may be acted upon in 85 the manner described by a single key.

SAMUEL GREEN.

In the presence of—

CHAS A. SKILLMAN,
JAMES RILEY.
